OTHA B. LANHAM, Inventor

By Richard Blawer ..

Attorney

UNITED STATES PATENT OFFICE.

OTHA B. LANHAM, OF PHILIPPI, WEST VIRGINIA.

WINDOW-CURTAIN POLE.

Application filed August 30, 1921. Serial No. 496,851.

To all whom it may concern:

Be it known that I, OTHA B. LANHAM, a citizen of the United States, residing at Philippi, in the county of Barbour and State of West Virginia, have invented certain new and useful Improvements in Window-Curtain Poles, of which the following is a specification.

The present invention consists of a window curtain support and has for an object 10 the provision of a device of this character adapted for use on windows of different sizes.

Another object of the invention is to provide 15 an effective support of this nature which may be quickly and conveniently applied to or removed from a window and will eliminate the use of nails, screws or like securing means.

20 The above and other objects of this invention will be in part described and in part understood from the following description of the present preferred embodiment of the invention taken in connection with the accompanying drawings wherein:—

Fig. 1 is a fragmentary front elevational view of a curtain support constructed in accordance with this invention illustrating its application;

30 Fig. 2 is a top plan view of the same; and

Fig. 3 is a detail enlarged front elevational view of one of the window embracing members illustrating its manner of connection to a pole end.

In the drawings in order to illustrate the application of this invention portions 4 of a window casing are shown.

The device of this invention consists of 40 a pair of window casing embracing members generally designated 5 each of which comprises a wire body made up of a plurality of strands. These strands consist of a base strand 6 substantially U-shaped which extends across and is engaged with the front face of the window casing. The legs of the U are twisted around the ends of a pair of strands 7 and the free terminals of the ends of the strand 7 as well as the terminals 45 of the legs of the U 6 are bent to provide hooks 8 the terminals of which are pointed for penetration in the outer margin of each window casing member. A wire

strand 9 is inter-winded with the ends of the strand 7 opposite to those which are 55 equipped with hooks 8 so as to provide a shank generally designated 10 which is imbedded in one end of a pole end 11. The outer end of the strand 9 is formed to provide a hook 12. This pole end may be suitably ornamented in a manner well known in the art and is adapted to project beyond the window casing.

The window embracing members 5 have the hooks 8 thereof urged into and retained 65 in the window casing by an elastic curtain holder 13 which in the present instance consists of a helical spring the ends of which are formed to provide hooks 14 which detachably engage the hooks 12. It is of 70 course to be understood that the elastic element 13 may be of any desired length, diameter and consistency dependent upon its usage. However, as a rule it can be made relatively small and is worked or run 75 through the hem of the curtain in a manner well known in the art. Of course the curtain may be engaged over the elastic element 13 in any desired manner having the pole ends 11 extended therefrom to give the 80 appearance of the usual ornamental curtain pole.

In using this device it is apparent that after the curtain has been engaged with the holder 13 and the hooks of the latter connected to the hooks 12 of the window embracing members, the pole ends 11 may be grasped by the hands of the operator and the curtain holder stretched until the members 5 are placed in the desired position 85 against the window casing following which the pole ends 11 are released and the members 5 anchored in the window casing by the contractile action of the curtain holder 13. The members 5 may be quickly disengaged 90 from the window casing in an obvious manner.

Various changes may be made in this device especially in the details of construction proportion and arrangement of parts 100 within the scope of the appended claim.

What is claimed is:—

A window curtain support including window casing embracing members each of which is equipped with casing penetrating 105 terminals, a shank on each of said members

one end of which is formed to provide an eye, a pole end engaging with each of said shanks and comprising elongated hand engaging portions, and a spring, the opposite 5 ends of which are formed to provide hooks engageable in the eyes of said casing embracing members to urge the pointed terminals of the latter into the window casing,

said pole ends being movable to disengage said casing embracing members.

In testimony whereof I affix my signature in presence of two witnesses.

OTH A. LANHAM.
